UNITED STATES PATENT OFFICE.

JOHN W. GURLEY, OF INDIANAPOLIS, INDIANA.

PUMP.

Application filed February 6, 1922. Serial No. 534,444.

To all whom it may concern:

Be it known that I, JOHN W. GURLEY, a citizen of the United States, residing at Indianapolis, in the county of Marion and 5 State of Indiana, have invented a new and useful Pump, of which the following is a specification.

It is the object of my invention to improve the operation of rotary pumps; and of 10 rotary fluid-pressure motors, for use as which my device is equally adapted. More specifically, the object is to produce a rotary pump of the type in which a rotor mounted eccentrically in a cylindrical casing is provided with a plurality of retractile casing-engaging parts, which can travel free of one another in a smooth path and remain always in contact with the inner surface of the casing and which will each be positively 15 20 25 30 35 40 45 50 55 60 65 70 75 80 85 90 95 100 105 110

pushed outward by the pushing inward of its opposite part if for any reason it fails to move outward otherwise; and, in addition, to provide retractile blades with special shoes which enable them to conform closely to the inner surface of the casing in their movements.

The accompanying drawing illustrates my invention; Fig. 1 is an end view of a pump embodying my invention, with its driving motor; Fig. 2 is a view transverse to the axis in the line of the discharge pipe, with part of the pump broken away to show the internal construction; Fig. 3 is a section on the line 3—3 of Fig. 2; Fig. 4 is a section on the line 4—4 of Fig. 2, with the rotor in one position; Fig. 5 is a fragmental view similar to Fig. 4, but with the rotor in another position; and Fig. 6 is a perspective view of the rotor, with the blades removed.

The pump has a casing formed of a circular cylindrical shell 10 and two end plates 11, the end plates being provided with suitable bearings 12 for the shaft 13 of the rotor 14. The rotor shaft 13 may be provided with any suitable driving means, such as a pulley 15 connectible by a belt 16 to a pulley 17 on the shaft of an electric motor 18. The bearings 12 are so arranged that the axis of the shaft 13 is eccentric with respect to the inner surface 19 of the shell 10, as is clear from Figs. 4 and 5, with the body of the rotor 14 tangent or nearly tangent to such surface 19 at one point only and spaced from such surface throughout the remainder of the circumference. The body of the rotor 14 substantially fits between the end plates 11,

as is clear from Fig. 2. This rotor body 14 is provided with a plurality of pairs of opposite longitudinal slots 20, two pairs or four slots being shown; and in each of these slots 20 is mounted a blade 21 which fits in said slot so as to be slidable in and out with respect to the shaft 13. The blades 21 also preferably fit between the end plates 11.

The movement of opposite blades toward each other is limited by pins 22 which project transversely through the shaft 13 from the bottom of the slots 20 into the opposite slots and are freely slidable along their own axes. With this arrangement, opposite blades cannot approach each other too closely, because when one blade 21 is pushed inward during the rotation of the rotor it acts upon the associated pins 22 and positively pushes outward the opposite blade 21 if for any reason such opposite blade tends to remain in. The pins 22 may be free from their associated blades, so that they do not interfere with the free outward movement of such blades beyond the positions to which they are pushed by the pins 22, with the pins 22 of such length that they touch the bottoms of both associated blades 22 when the latter are closest together, as the vertical blades 21 are shown in Fig. 5; but preferably they are fastened to such blades.

The blades 21 do not directly engage the surface 19, as because of the aforesaid eccentricity of the surface 19 with respect to the rotor the blades themselves must rock slightly with respect to such surface as the rotor rotates, so that the contact obtained if the blades directly engage such surface is not the best. To make a surface contact, therefore, I provide each blade 21 with a contact shoe 23 at its outer edge, which contact shoe then directly engages the surface 19. This contact shoe consists of a bar of the length of the blade 21, having a curved outer surface bearing against and of the same curvature as the surface 19, so that a good seating of the contact shoe against the surface 19 is obtained. The contact shoe has an inner convex surface, forming a segment of a cylinder, resting in a corresponding cylindrical concave surface 24 in the outer edge of the blade 21. The common axis of the surface 24 and of the engaging surface of the shoe 23 preferably lies substantially on the surface 19, or close thereto; and if it is not on such surface I prefer that such axis be radially outward beyond such

surface 19. This makes a construction in which the shoe 23 need not project circumferentially beyond the side surfaces of the blade 21, so that it can recede into the slot 20 with the blade, as shown at the right in Fig. 5, while still making a structure in which the shoe is stable in its seating and will swing properly from side to side without dropping out as the rotor rotates.

10 It is only necessary that opposite shoes be free of each other for outward movement, and it is neither necessary nor desirable that the opposite blades 21, which do not engage the surface 19, be free from the pins 22; though it is not essential that the blades be inseparable from such pins. Indeed, with the contact shoes, the blades 21, even if separable from the pins 22, remain in contact with the ends of such pins under many conditions; by reason of the fluid pressure against the surfaces 24 of such blades due to the back pressure of the fluid being pumped, and perhaps for other reasons; at the same time, the contact shoes 23 are held by 25 the same fluid pressure, as well as by centrifugal force, in firm seating engagement with the surface 19 of the shell, and at certain points move somewhat outward and slightly circumferentially backward with relation to 30 the blades 21 as is illustrated in the left-hand blade of Fig. 5. This always takes place if the blades 21 are fastened to the pins 22, as they may be and preferably are; and it takes place under certain conditions 35 of pressure and speed even if the blades are free from the pins 22. In either case, the opposite shoes which engage the surface 19 are free from each other so that they move outward independently, but are associated 40 through the pins 22 and their associated blades so that such shell-engaging parts can not approach too closely together. As the rotor rotates, the distance between two opposite shoes varies, because they and their 45 associated blades are on a diametral plane of the rotor, and when they are in one position (horizontal in Fig. 5) they are on a diameter of the circular-cylindrical shell, while in all other positions they are on a chord of 50 such circular-cylindrical shell, which chord is the shortest in the vertical position shown in Fig. 5, when the blades and shoes are perpendicular to the first-named shell diameter. This causes the space between each 55 shoe and its associated blade to open and close alternately, as the rotor rotates, the opening of such space being obtained by centrifugal force and by the back pressure of the fluid being pumped, both of which 60 act to produce a firm seating of the shoe against the inner surface of the shell and also against some part of the concave surface in the outer edge of the blade, with the necessary backward circumferential shifting of 65 the shoe in relation to the blade to accomplish

this. When the contact shoes 23 do move outward and backward with relation to their blades 21 as stated, they not only remain in contact with the surface 19 throughout their outer surfaces, but also remain in contact 70 with at least a line on the surfaces 24 of their associated blades, so that a tight seal is maintained and backward leakage past the blades is largely prevented.

The shell 10 is provided with tangential 75 inlet and outlet conduits 25 and 26, which project tangentially from the shell 10 on opposite sides of and substantially parallel to the radius of the shell or rotor at the point where they are tangent to each other, as is clear from Figs. 4 and 5. The inlet and outlet conduits are on opposite sides of that radius, so that the water or other fluid being pumped may enter the shell by the inlet conduit and pass circumferentially 80 around the shell inside thereof for only half a revolution, and leave tangentially by the outlet conduit, with no material change of direction save during such half revolution within the shell. The inlet and exhaust 85 conduits are each elongated axially of the shell and narrowed circumferentially of the shell, as is clear from Figs. 3 and 4, so that they provide an oval opening into the shell; and this oval form is gradually tapered into 90 a circular form for receiving the supply and discharge pipes 27 and 28, as is also clear from Figs. 3 and 4. This makes a stream-line passage with a minimum of frictional 95 resistance and a minimum of speed change 100 for the fluid flow.

In operation, the rotor 14 is driven in the direction of the arrow, as by the motor 18. As the rotor rotates, the several pump chambers formed by the retractile blades 21 and 105 between the surface 19 and the outer surface of the rotor 14 are first enlarged from a minimum to a maximum and then decreased in size from a maximum to a minimum, being in communication with the intake conduit 25 while enlarging and with the exhaust conduit 26 while diminishing in size; so that fluid is drawn in through the supply pipe 27 and inlet conduit 25 into the pump shell 10 in the successive chambers and then discharged through the outlet conduit 26 and 110 discharge pipe 28. Because of the close fit which is maintained within the inner surface 19 by the shoes 23, and of the positive out-forcing tendency of the pins 22 on the outwardly moving blades if for any reason they fail to move, there is very little leakage, and both at high suction and a high pressure 115 are obtained. The leakage loss is further reduced by the fact that the blades 21 fit 120 the slots 20 closely, and that opposite slots 20 are connected only by the small holes which receive and are substantially filled by the pins 22. By reason of the stream-line 125 passage provided, with only a single half- 130

turn in it for the fluid, the efficiency of the pump is high.

I have described my device as a pump; but it is capable of efficient use, without change, as a rotary fluid-pressure motor. My claims are intended to cover the actual device, regardless of the use to which it is put.

I claim as my invention:

- 10 1. A rotary pump, comprising a circular-cylindrical shell, a rotor body mounted eccentrically in said shell and having a plurality of pairs of diametrically opposite longitudinal slots in its surface, blades mounted in said slots for radial sliding therein, opposite blades having means for holding them at least a predetermined distance apart, said blades being provided with longitudinal grooves in their outer edges, wearing shoes pivotally mounted on the outer edges of said blades in said grooves, said wearing shoes being bodily separable from their associated groove surfaces and circumferentially shiftable relatively thereto to maintain partial contact, and the shape of the inner surface of said cylindrical shell being such that the distance between the lines where a diametral plane of the rotor intersects said inner shell-surface varies as such plane rotates so that there will be a variable separation and circumferential shifting between each shoe and its associated groove as the rotor rotates and the shoe will be forced against said inner shell-surface by fluid pressure acting between the shoe and the blade as well as by centrifugal force. 65
- 15 2. A rotary pump, comprising a cylindrical shell, a rotor body mounted eccentrically in said shell and having a plurality of pairs of diametrically opposite longitudinal slots in its surface, blades mounted in said slots for radial sliding therein, opposite blades having means for holding them at least a predetermined distance apart, said blades being provided with longitudinal grooves in their outer edges, wearing shoes pivotally mounted on the outer edges of said blades in said grooves, said wearing shoes being bodily separable from their associated groove surfaces and circumferentially shiftable relatively thereto to maintain partial contact, and the shape of the inner surface of said cylindrical shell being such that the distance between the lines where a diametral plane of the rotor intersects said inner shell-surface varies as such plane rotates so that there will be a variable separation and circumferential shifting between each shoe and its associated groove as the rotor rotates and the shoe will be forced against said inner shell-surface by fluid pressure acting between the shoe and the blade as well as by centrifugal force. 70
- 20 3. A rotary pump, comprising a cylindrical shell, a rotor body mounted eccentrically in said shell and having a plurality of pairs of diametrically opposite longitudinal slots in its surface, blades mounted in said slots for radial sliding therein, opposite blades having means for holding them at least a predetermined distance apart, said blades being provided with longitudinal grooves in their outer edges, wearing shoes pivotally mounted on the outer edges of said blades in said grooves, said wearing shoes being bodily separable from their associated groove surfaces and circumferentially shiftable relatively to them to maintain partial contact as the distance between opposite wearing shoes varies during the rotation of the rotor; so that fluid pressure may act between said wearing shoes and blades to seat the wearing shoes against the shell. 75
- 25 4. A rotary pump, comprising a cylindrical shell, a rotor body mounted eccentrically in said shell and having a plurality of pairs of diametrically opposite longitudinal slots in its surface, blades mounted in said slots for radial sliding therein, opposite blades having means for holding them at least a predetermined distance apart, said blades being provided with longitudinal grooves in their outer edges, wearing shoes pivotally mounted on the outer edges of said blades in said grooves, said wearing shoes being bodily separable from their associated groove surfaces and circumferentially shiftable relatively thereto to maintain partial contact, and the shape of the inner surface of said cylindrical shell being such that the distance between the lines where a diametral plane of the rotor intersects said inner shell-surface is at least at times in the rotor rotation greater than the distance between the outer surfaces of two opposite wearing shoes when said opposite wearing shoes and the parts interposed between them are in full seating contact, so that at least at such times in the rotor rotation a wearing shoe will be separated from and circumferentially shifted on its seat in its associated blade-groove and pushed outward against the inner shell surface by the action of fluid pressure between it and the associated blade-groove as well as by centrifugal force. 80
- 30 5. A rotary pump, comprising a cylindrical shell, a rotor body mounted eccentrically in said shell and having a plurality of pairs of diametrically opposite longitudinal slots in its surface, blades mounted in said slots for radial sliding therein, opposite blades having means for holding them at least a predetermined distance apart, said blades being provided with longitudinal grooves in their outer edges, wearing shoes pivotally mounted on the outer edges of said blades in said grooves, said wearing shoes being bodily separable from their associated groove surfaces and circumferentially shiftable relatively thereto to maintain partial contact, and the shape of the inner surface of said cylindrical shell being such that the distance between the lines where a diametral plane of the rotor intersects said inner shell-surface is at least at times in the rotor rotation greater than the distance between the outer surfaces of two opposite wearing shoes when said opposite wearing shoes and the parts interposed between them are in full seating contact, so that at least at such times in the rotor rotation a wearing shoe will be separated from and circumferentially shifted on its seat in its associated blade-groove and pushed outward against the inner shell surface by the action of fluid pressure between it and the associated blade-groove as well as by centrifugal force. 85
- 35 6. The combination set forth in claim 2, wherein the groove-engaging surface of each shoe is a cylindrical segment of a radius at least as great as the maximum distance of said surface from the other side of the shoe. 90
- 40 7. The combination set forth in claim 2, wherein the groove-engaging surface of each shoe is a cylindrical segment of a radius at least as great as the maximum distance of said surface from the other side of the shoe. 95
- 45 8. The combination set forth in claim 2, wherein the groove-engaging surface of each shoe is a cylindrical segment of a radius at least as great as the maximum distance of said surface from the other side of the shoe. 100
- 50 9. The combination set forth in claim 2, by the action of fluid pressure between the shoes and the groove surfaces of the blades. 105
- 55 10. The combination set forth in claim 2, wherein the groove-engaging surface of each shoe is a cylindrical segment of a radius at least as great as the maximum distance of said surface from the other side of the shoe. 110
- 60 11. The combination set forth in claim 2, wherein the groove-engaging surface of each shoe is a cylindrical segment of a radius at least as great as the maximum distance of said surface from the other side of the shoe. 115
- 65 12. A rotary pump, comprising a cylindrical shell, a rotor body mounted eccentrically in said shell and having a plurality of pairs of diametrically opposite longitudinal slots

In witness whereof, I have hereunto set my hand at Indianapolis, Indiana, this 3rd day of February, A. D. one thousand nine hundred and twenty-two.

JOHN W. GURLEY.
